UNITED STATES PATENT OFFICE.

JOHN LLOYD WILLIAMS, OF SHENANDOAH, PENNSYLVANIA.

MINER'S SAFETY-LAMP.

SPECIFICATION forming part of Letters Patent No. 290,510, dated December 18, 1883.

Application filed August 17, 1883. (Model.)

To all whom it may concern:

Be it known that I, JOHN L. WILLIAMS, of Shenandoah, in the county of Schuylkill and State of Pennsylvania, have invented a new and Improved Miner's Safety-Lamp, of which the following is a full, clear, and exact description.

The object of my invention is to provide a new and improved attachment for miners' lamps, by means of which they can be extinguished very quickly without requiring the lamp to be opened.

Reference is to be had to the accompanying drawings, forming part of this specification, in which similar letters of reference indicate corresponding parts in all the figures.

Figure 1 is a side view of a miner's lamp provided with my improvement. Fig. 2 is a plan view of the same. Fig. 3 is a cross-sectional elevation of the same. Fig. 4 is a perspective view of the sliding sleeve on the wick-tube. Fig. 5 is a perspective view of the wick-tube.

The miner's safety-lamp A is provided with a longitudinally-slotted wick-tube, B, and a picker-wire, C, extending through a vertical tube, C', to the bottom of the lamp; from where it can be manipulated, all in the usual manner. I provide the lamp with an additional vertical tube, D', extending from the burner E to the bottom and terminating in a recess, F, formed in the bottom of the lamp. A wire, D, is passed loosely through the tube D', and to the upper end of the said wire a sleeve or tube, G, is fastened, which fits on the wick-tube B, and is adapted to surround the same. The flange B' of the wick-tube is provided with a notch or recess, a, through which the tube D' can pass. When the bottom edge of the sleeve G rests upon the wick-tube flange B', the wick-tube projects slightly above the upper end of the sleeve and the lamp burns unmolested. If the flame is to be extinguished quickly, the lower end of the wire D is seized and pushed upward to cause the sleeve to project above the upper end of

the burner-tube. It then extinguishes the flame.

It is of great importance to be able to extinguish the flame of a miner's lamp very quickly in case fire-damp accumulates, so as to prevent explosions. Heretofore the wick has been drawn into the wick-tube by means of the picker-wire C; but by this means the lamp could not be extinguished quickly, especially if the miners became excited, which is always more or less the case when fire-damp accumulates. As it is absolutely dangerous to open the lamp, the means for extinguishing the flame must be so arranged that they can be operated without opening the lamp.

Having thus described my invention, what I claim as new, and desire to secure by Letters Patent, is—

1. The combination, with a lamp, of a sleeve or tube adapted to slide on the wick-tube, and a wire secured to the said sleeve or tube and passing through the lamp from top to bottom, substantially as herein shown and described.

2. The combination, with a lamp having a recess in the bottom, of a sleeve or tube on the wick-tube and a wire extending from the said tube into the recess in the bottom of the lamp, substantially as herein shown and described.

3. The combination, with a miner's lamp, of the tube D', extending from top to bottom, the wire D in the said tube, and the sleeve G, secured to the upper end of the wire D, and adapted to slide on the wick-tube, substantially as herein shown and described.

4. The combination, with a miner's lamp, of the tube D', extending from top to bottom, the wire D in the said tube, the sleeve G, secured on the upper end of the wire, and of the wick-tube B, having a flange, B', provided with a notch, a, for the tube D', substantially as herein shown and described.

JOHN LLOYD WILLIAMS.
